BELT RACK OR SIMILAR ARTICLE

Lloyd E. Anderson, Sr., 813 Alden Drive,
Pittsburgh, Pa.

Filed Sept. 9, 1960, Ser. No. 62,087

Term of patent 14 years

(Cl. D33—8)

FIGURE 1 shows an isometric view of a belt rack or similar article;

FIGURE 2 shows a side elevational view thereof; and FIGURE 3 shows a plan view thereof.

The dotted lines shown in FIG. 1 are for illustrative purposes only.

I claim:

The ornamental design for a belt rack or similar article, substantially as shown and described.
